UNITED STATES PATENT OFFICE.

WILLIAM S. FERRIS, OF ELKHART, INDIANA.

TABLET ARMCHAIR.

Application filed July 27, 1925. Serial No. 46,199.

This invention relates to improvements in tablet arm chairs and consists of the matters hereinafter described and more particularly pointed out in the appended claim.

5 The object of the invention is to so construct a tablet arm chair as to prevent its easy tipping when a pressure or weight is imposed upon the tablet arm which usually projects a considerable distance beyond the 10 plane of the front and one side of the chair seat.

This object of the invention, as well as others together with the many advantages thereof will more fully appear as I proceed 15 with my specification.

In the drawings:—

Fig. 1 is a perspective view of a tablet arm chair embodying my invention.

Fig. 2 is a top plan view thereof.

20 Referring now in detail to that embodiment of the invention illustrated in the accompanying drawing:—1 indicates as a whole the seat frame of the chair which is substantially rectangular in plan and to 25 which is secured a seat 2 preferably of a width greater than its depth. To the side members of the seat frame near the rear ends thereof are secured upwardly and rearwardly inclined arms 3—3 which are connected 30 together at their top ends by a back rest member 4. Said arms are held in the desired position by means of brace bars 5—5 which together with the arms permit the back rest to be adjusted into the desired position. 35 6 indicates the tablet arm usually located on the right hand side of the chair. Said tablet arm is adjustably supported midway between its ends on the top end of a post 7 rising from the front right hand corner of 40 the seat frame and secured thereto in any suitable manner. The rear end of said tablet arm which is narrower than the front end is adjustably secured to the rear right back rest supporting arm by a strap 7^a so that the 45 tablet arm may be adjusted both as to its height above the seat and also as to its angular inclination with respect thereto. As is apparent from Figs. 1 and 2, the comparatively wide front end of the tablet arm projects a substantial distance beyond the plane 50 of the front end and associated side of the seat frame. In the chairs of this kind as heretofore made when a pressure or weight was imposed upon the front end of the tablet 55 arm, tipping of the chair most invariably resulted.

To overcome this easy tipping tendency under such conditions as are above mentioned, I provide a novel arrangement of the legs of the chair as will now be described:—8 60 indicates the left front leg, 9 the right front leg and 10—10 the rear legs, all of which are made of tubular metal stock. The top ends of all of said legs are preferably straight and vertically disposed and receive downwardly extending cylindrical extensions 11, 65 one at and depending from each of the four corners of the seat frame. Any suitable means may be provided to secure said extensions in the top ends of the associated legs 70 so that the height of the seat may be easily adjusted to the comfort of the occupant.

The left front leg is preferably straight and extends in a vertical plane throughout its length, while the bottom ends of the rear legs are bent or offset rearwardly in planes parallel with the sides of the seat frame to terminate in a plane spaced rearwardly from that of the rear member of the seat frame. This increases the "spread" of said rear legs 80 so that the chair will not easily tip over rearwardly, should the occupant lean heavily against the back rest.

The front right leg is of a peculiar formation to the extent that its bottom end is bent to extend forwardly of the plane of the front member of the seat frame and also to extend in a plane to the outside of the right hand side member of the seat frame, so that when viewed in plan the bottom end extends 90 in a diagonal plane as best shown in Fig. 2. By this construction said bottom end of the front right leg is located in a vertical plane arranged near the front end of the tablet arm within the area defined by the forward 95 portion of said tablet arm. In this manner such pressure or weight as is imposed upon the front end of the tablet arm is resisted in its tendency to tip over the chair. The straight or vertical top end portions of all of said legs are connected together by suitable braces 11 thus providing a strong and rigid leg structure.

Tablet arm chairs are now coming into great use in class rooms, lunch rooms and other places and with the front legs arranged in the plane of the front of the seat, the easy tipping is a great annoyance. However with my improved construction, the positioning of the bottom end of the 110 leg associated most directly with the tablet, which as herein described is the right

front leg, eliminates said tipping tendency. Ordinarily an occupant in arising from and leaving a tablet chair will assist himself by placing his right hand upon the tablet arm near the front end thereof. Such action on the part of the occupant usually caused a tipping or wobbling of tablet arm chairs as heretofore made but however, with my improved construction this tipping is easily 10 counteracted and the chair remains stationary.

Again by offsetting the bottom end of the leg most directly associated with the tablet arm, more foot room is provided for the occupant as will be apparent.

While in describing my invention I have referred to certain details of mechanical construction and arrangement of parts, I do not wish to be limited thereto except as may 20 be pointed out in the appended claim.

I claim as my invention:—

A chair embodying therein, a seat frame, pairs of front and rear legs connected to the corners of the seat frame, a tablet arm arranged along the right hand side and above the seat frame and having a portion extending forwardly of the same, the bottom end of the right front leg extending diagonally outward and engaging the floor at a point within the area defined by the forward portion of the tablet arm, the bottom ends of the rear legs being offset rearwardly to extend beyond the vertical plane of the rear end of the seat frame while the other front leg member is straight and an upright member rising from that corner of the seat frame associated with said right front leg for supporting said tablet arm.

In testimony whereof, I have hereunto set my hand, this 11th day of July, 1925.

WILLIAM S. FERRIS.
